AUTOMATIC SCISSORS

Joe Brancato and Dominick Scalese,
Barnesboro, Pa.

Application March 19, 1938, Serial No. 196,990

4 Claims. (Cl. 30—228)

This invention relates to automatic scissors, and it is an object of the invention to provide a tool of this kind comprising two cutting blades supported for relative swinging movement one 5 toward the other together with power driven means for imparting the desired movement to the swinging blades.

It is also an object of the invention to provide a tool of this kind wherein the swinging blade 10 after completing its cutting movement is initially moved in reverse by the power driven mechanism but further returned to its open position through the instrumentality of a spring, said last named movement independently of the power driven 15 mechanism facilitating the use of the scissors.

Another object of the invention is to provide automatic scissors constructed, assembled and operated in a manner permitting the scissors to be put to the same uses as the conventional type 20 of hand operated scissors.

The invention consists in the details of construction and in the combination and arrangement of the several parts of our improved automatic scissors whereby certain important advantages are attained and the device rendered 25 simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawing, wherein:

35 Figure 1 is a view in top plan of automatic scissors constructed in accordance with an embodiment of our invention;

Figure 2 is a view in side elevation of the tool as illustrated in Figure 1 with portions in section; 40 Figure 3 is a view similar to Figure 1 with the portions broken away;

Figure 4 is a sectional view taken substantially on the line 4—4 of Figure 2.

As disclosed in the accompanying drawing, H 45 denotes a hollow head having a removable front plate 1 and a removable top plate 2. The top plate 2 is held in applied position by the removable screws 3 or the like while the front plate 1 is maintained in position by the screws 4 which extend through the front plate 1 and have operative engagement with a bar 5 interposed between and connecting the side walls of the head H at the upper portion thereof and adjacent the front edges of said side walls. These plates 1 and 2 are removable to facilitate the assembly 50

of the structure and to allow access thereto for the purpose of lubrication, repair or as may otherwise be desired.

The back wall of the head H has extending outwardly therefrom a bearing 7 for a shaft 8. The outer end portion of this shaft 8 is in driven connection with a flexible shaft 9 adapted to be coupled to a suitable source of power. This flexible shaft is of a conventional type and is extended through a flexible conduit 10 as is well known. The shaft 8 extends within the head H and the portion of the shaft within the head has fixed thereto for rotation therewith a disk 11 carrying an outstanding crank pin 12 carrying an anti-friction roller 14.

Overlying the bottom wall 15 of the head H is the rear end portion of a scissors blade A. This blade A is held to the bottom wall 15 by the threaded members 16 disposed through the bottom wall 15 and engaging the rear or overlying 20 end portion of the blade A. Associated with this blade A is a second blade B pivotally connected, as at 17, with the blade A and more particularly the portion of said blade overlying the bottom wall 15 of the head H. The blade B is free to 25 swing toward or from the blade A whereby said blade will cooperate to effect the desired cutting action. The blade B has a portion 18 extending rearwardly of the head H beyond the pivot 17 and secured to this portion 18 by rivets 19 or 30 the like is a plate 20. This plate 20 has extending upwardly therefrom a pair of arms 21 and 22 spaced apart in a direction transversely of the adjacent portion of the blade B. These arms 21 and 22 are laterally disposed with respect to 35 the outer face of the blade B and longitudinally curved with the curvature of the inner arm 21 on a radius different from the radius of the outer arm 22 so that the space between the arms 21 and 22 increases from the blade B.

The pin 12 with its roller 14 is positioned between the arms 21 and 22 and as the shaft 8 is rotated the pin 12, or more particularly the roller or sleeve 14 carried thereby, will contact with the arm 21 and positively swing the blade B toward and into cutting relation with respect to the blade A. This action will be maintained until the pin 12 reaches substantially its high point and as the pin 12 moves away from the arm 21 a retractile member or spring 23 operates to impart outward swinging movement to the blade B. This spring 23 is anchored at one end, as at 24, to the arm 21 and at its opposite end portion is anchored, as at 25, to a side wall of the head.

If, for any reason, the blade B should refuse to act under the tension of the spring 23 as by undue resistance being offered by work caught between the overlying blades A and B at the conclusion of a cutting action by the blade B, the arm 22 will be in a positon to allow the pin 12 or its sleeve or roller 14 to have contact therewith and thus provide positive means through the action of the disk 11 for causing the blade B to return to its open position.

It is to be noted that the threaded members 16 are so positioned that one of said members 16 has contact with the portion of the blade B inwardly of its pivot 17. By proper adjustment of this particular member 16 the blade B may be readily adjusted or set with respect to the blade A.

From the foregoing description it is thought to be obvious that automatic scissors constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:

1. Mechanically operated scissors comprising a hollow head, a rotatable shaft carried by the head and extending therein, means for rotating the shaft, a disk carried by the shaft within the head, a pair of pivoted blades having end portions extending within the head, means for anchoring one of the blades to the head, outstanding spaced arms carried by the end portion of the second blade within the head, said arm being laterally disposed with respect to the outer face of the blade, a part carried by the disk extending between the arms, means within the head for normally urging one of the arms into engagement with the part carried by the disk for moving the second blade in one direction, said part carried by the disk contacting with the second arm upon failure of said means to function.

2. Mechanically operated scissors comprising a hollow head, a rotatable shaft carried by the head and extending therein, means for rotating the shaft, a disk carried by the shaft within the

head, a pair of pivoted blades having end portions extending within the head, means for anchoring one of the blades to the head, outstanding spaced arms carried by the end portion of the second blade within the head, said arm being laterally disposed with respect to the outer face of the blade, a part carried by the disk extending between the arms, means within the head for normally urging one of the arms into engagement with the part carried by the disk for moving the second blade in one direction, said part carried by the disk contacting with the second arm upon failure of said means to function, said arms being so constructed and arranged to provide an increasing space therebetween from the blade to the outer ends of said arms.

3. Mechanically operated scissors comprising a hollow head, a rotatable shaft carried by the head and extending therein, means for rotating the shaft, a disk carried by the shaft within the head, a pair of pivoted blades having end portions extending within the head, means for anchoring one of the blades to the head, outstanding spaced arms carried by the end portion of the second blade within the head, said arm being laterally disposed with respect to the outer face of the blade, a part carried by the disk extending between the arms, and a retractable member operatively engaged with one of the arms to normally maintain the arm in contact with the part of the disk for moving the second blade in one direction, said part contacting with the second arm to move the blade when the spring fails to function.

4. Mechanically operated scissors comprising a hollow head including a fixed bottom plate and a removable front plate, a rotatable disk supported within the head, a crank pin carried by the disk, a pair of pivoted blades having end portions extending within the head, means for anchoring one of the blades to the bottom plate of the head, the second blade having outstanding spaced arms extending laterally from the outer face thereof and between which the crank pin of the disk extends, means for normally maintaining one of said arms in contact with the crank pin and for imposing movement in one direction on the blade, the crank pin contacting with the second arm to swing the blade when the means becomes ineffective.
